CLAIM

The ornamental design for a passenger seating apparatus, as shown and described.

DESCRIPTION

FIG. 1 is a front perspective view of a passenger seating apparatus;

FIG. 2 is a front elevation view of the passenger seating apparatus of FIG. 1;

FIG. 3 is a top plan view of the passenger seating apparatus of FIG. 1;

FIG. 4 is a bottom plan view of the passenger seating apparatus of FIG. 1;

FIG. 5 is a right side elevation view of the passenger seating apparatus of FIG. 1;

FIG. 6 is a left side elevation view of the passenger seating apparatus of FIG. 1;

FIG. 7 is a rear elevation view of the passenger seating apparatus of FIG. 1;

FIG. 8 is a rear perspective view of the passenger seating apparatus of FIG. 1;

FIG. 9 is a rear elevation view showing a second embodiment of the passenger seating apparatus in which the other views shown in FIGS. 1 through 3 as well as FIGS. 5 and 6 would be identical; and,

FIG. 10 is a rear perspective view thereof.

Portions of FIGS. 1 through 10 are shown in broken lines illustrating portions of the article of manufacture that form no part of the claimed design.
